Des. 184,708
Patented Mar. 31, 1959

184,708

VENTILATOR FOR VEHICLES

Horace M. Burke, Miami, Fla.

Application March 4, 1957, Serial No. 45,061

Term of patent 7 years

(Cl. D14—6)

Figure 1 is a side elevational view of a ventilator for vehicles, showing my new design, the opposite side having substantially the same appearance.

Figure 2 is a top plan view thereof;

Figure 3 is a bottom plan view thereof.

Figures 4 and 5 are front and rear end views, respectively thereof.

I claim:

The ornamental design for a ventilator for vehicles, substantially as shown.
